US00D534830S

(12) **United States Design Patent** (10) **Patent No.:** **US D534,830 S**
(45) **Date of Patent:** **** Jan. 9, 2007**

(54) **NOVELTY DEVICE**

(75) Inventor: **John Anastasiadis**, Wilmington, DE
(US)

(73) Assignee: **Hayloft Enterprises, Inc.**, Wilmington, DE (US)

(**) Term: **14 Years**

(21) Appl. No.: **29/251,932**

(22) Filed: **Jan. 13, 2006**

(51) **LOC (8) Cl.** **11-01**

(52) **U.S. Cl.** **D11/84; D11/125; D23/367**

(58) **Field of Classification Search** **D11/211, D11/221, 223, 225, 238, 241, 1, 2, 7, 8, 44, D11/48, 63, 67, 75, 79, 81, 86, 115, 117, D11/121, 125, 130, 131, 133, 139, 140, 157, D11/164; D1/104, 106, 115, 127; D3/211; D9/645, 646; D21/386, 465, 467, 483; D23/366–369; D26/4, 14, 19, 32, 47, 57, 73, 101, 127, 154, D26/156; D28/4, 5, 6, 8.1, 8.2; 428/7–12, 428/15, 17, 21, 28, 905; 63/1.11–43; 239/34–60; 362/104, 122, 806**

(57) **CLAIM**

The ornamental design for the novelty device, as shown and described.

DESCRIPTION

FIG. 1 is a perspective view of the novelty device; FIG. 2 is a front elevational view thereof; FIG. 3 is a right side elevational view thereof with the left side elevational view being the same; FIG. 4 is a top plan view thereof; and, FIG. 5 is a bottom plan view thereof.

An alternative embodiment of my design is similar to the design embodiment shown in FIGS. 1–5, but made with a translucent material.
